UNITED STATES PATENT OFFICE.

CHARLES C. TAYLOR, OF PHILADELPHIA, PENNSYLVANIA.

COMBINED ENVELOP AND COIN-CARRIER.

1,108,274.

Specification of Letters Patent. Patented Aug. 25, 1914.

Application filed April 15, 1913. Serial No. 761,253.

To all whom it may concern:

Be it known that I, CHARLES C. TAYLOR, a citizen of the United States, residing in the city of Philadelphia, county of Philadelphia, State of Pennsylvania, have invented a certain new and useful Combined Envelop and Coin-Carrier, of which the following is a specification.

My invention relates to a combined envelop and coin-carrier, and it has for its object to provide an envelop and coin-carrying or holding pocket in a single structure embodying extreme simplicity and efficiency.

It is also an object of my invention to provide a construction which may be manufactured cheaply.

A construction embodying my invention affords means whereby a receptacle is provided for a letter, printed matter, or paper money; also a receptacle for coins, whereby the sending of such letter, printed matter or paper money and coin through the mails is rendered very convenient.

My invention comprehends the construction now to be described and which is illustrated in the accompanying drawing, in which,—

Figure 1 is a view showing the rear side of the envelop with the closing flap extended and with the pocket in position for the insertion of a coin, and also showing a coin partially inserted; Fig. 2 is a similar view but showing the coin fully inserted and the pocket turned down upon the rear side of the envelop, and also showing in dot and dash lines a letter partially inserted in the envelop; Fig. 3 is a view of a blank with adhesive substance applied at the proper places and ready to be folded to form the envelop and pocket; and Fig. 4 is a transverse sectional view of the structure with the pocket folded down as shown in Fig. 2 and with the closing flap folded down over the same and sealed.

Referring to the drawings,—1 designates the front fold or address side of the envelop and 2 the back fold of the same.

3 designates the closing flap, which may be of substantially the same width and length as the body of the envelop. Said flap is formed by extending one edge of the front fold 1, as illustrated. Its inside edge portions are provided with adhesive 4. The opposite ends of the front fold 1 are extended to form flaps 5 having an adhesive substance thereon as indicated at 6.

In forming the envelop the back fold 2 is folded over on to the front fold. The flaps 5 are then folded over on to the ends of the said back fold 2 and secured thereto as shown in Figs. 1 and 2 to hold the same in such folded-over position. The edge of the back fold 2 is extended as shown at 7 in Fig. 3 and a portion of the side edge of such extension is extended and covered with adhesive as shown at 8. In forming the pocket the corner 9 is folded over along the dash line 10 while the corner 11 is folded along the dash line 12 so that the coated surface at 8 overlaps the edge 13 of the triangular corner portion 9. In this way a triangular pocket is formed for the reception of a coin or other small article. The opening of the said pocket is along the line of the edge of the back fold 2.

14 designates a coin which is shown in Fig. 1 as being partially inserted in the pocket and in Fig. 2 as being wholly within such pocket. In said Fig. 2 the pocket is turned down over the back fold 2 of the envelop. Also in Fig. 2, 15 indicates a letter or similar article partially inserted in the envelop. The envelop is closed and the pocket retained in the position shown in Figs. 2 and 4 by folding the closing flap 3 down as shown in Fig. 4 and securing the coated edges thereof to the back fold 2. Both the side and end edge portions of the closing flap 3 are coated with adhesive so that the pocket is completely inclosed and is inaccessible unless the closing flap 3 be lifted and the letter thereby partially or completely unsealed.

In a structure embodying my invention, the coin is protected on one side by at least three thicknesses of material, namely one side of the pocket and the front and back folds of the envelop, and on the other side by two thicknesses,—one side of the pocket and the closing flap 3.

I claim:

1. A combined envelop and pocket comprising the front and back folds of the envelop, a pocket attached to the edge of the back fold, and a closing flap attached to the front fold and adapted to be folded over the pocket and secured to the body of the envelop to hold the said pocket against the back fold and to close the envelop.

2. A combined envelop and pocket for carrying a coin or similar article comprising front and back folds, a closing flap formed

from an extension of the free edge of the front fold, which flap may be of substantially the same size as the front and back folds, and a pocket formed from an extension of the free edge of the back fold, the opening into said pocket being along the line of the free edge of said back fold and adapted to be closed by folding said pocket over upon the back fold, and the said envelop adapted to be closed and the pocket secured in folded-over position by said closing.

3. A combined envelop and pocket comprising front and back folds, the free edge 15 of the back fold being extended and having its corner portions folded along lines at right angles to each other, one edge of one of the folded over corner portions overlapping the edge of the other folded over portion, the said folded over portions forming 20 a pocket which pocket is adapted to be folded into parallel relation with respect to the front and back folds and the free edge of the front fold being extended to form a 25 flap which is adapted to be folded over and secured to the body portion of the envelop to close the same and to hold the said pocket in position.

4. A combined envelop and pocket comprising front and back folds, the free edge of the back fold being extended, one portion thereof to a greater extent than the other portion thereof, the corner portions of

the said extensions being folded against the said extension, the extended edge of one of 35 the said folded over corner portions being overlapped by the edge of the other folded over portion, the said folded over portions forming a pocket which is adapted to be folded into parallel relation with respect 40 to the front and back folds and the free edge of the front fold being extended to form a flap which is adapted to be folded over against and to be secured to the body portion of the envelop to close the same and 45 to hold the said pocket in position.

5. A combined envelop and pocket comprising the front and back folds of the envelop, the free edge of the back fold of the said envelop being extended and folded to 50 form a pocket, which pocket is adapted to be folded into parallel relation with respect to the front and back folds of the envelop, and a flap formed by extending the free edge of the front fold of the said 55 envelop, which flap is adapted to be folded over against and secured to the body portion of the said envelop to close the same.

In testimony that I claim the foregoing as my invention, I have hereunto signed my 60 name this 14th day of April, A. D. 1913.

CHARLES C. TAYLOR.

In the presence of—

GEO. H. WEIDNER,
CARRIE E. KLEINFELDER.
